Primary Examiner—M. H. Tung*Assistant Examiner*—Lavone D. Tabor*Attorney, Agent, or Firm*—Head, Johnson & Kachigian[57] **CLAIM**

The ornamental design for a toothbrush with handle, as shown and described.

DESCRIPTION

FIG. 1 is a front elevational view of a first embodiment of our design showing our toothbrush with handle;

FIG. 2 is a top plan view thereof;

FIG. 3 is a bottom plan view thereof;

FIG. 4 is a right side elevational view of our design, the left side elevational view being the mirror opposite thereof; and FIG. 5 is a rear elevational view thereof.

FIG. 6 is a front elevational view of a second embodiment of our design showing our toothbrush with handle;

FIG. 7 is a top plan view thereof;

FIG. 8 is a bottom plan view thereof;

FIG. 9 is a right side elevational view of our design, the left side elevational view being the mirror opposite thereof, and FIG. 10 is a rear elevational view thereof.

FIG. 11 is a front elevational view of a third embodiment of our design showing our toothbrush with handle;

FIG. 12 is a top plan view thereof;

FIG. 13 is a bottom plan view thereof;

FIG. 14 is a right side elevational view of our design, the left side elevational view being the mirror opposite thereof; and, FIG. 15 is a rear elevational view thereof.
